UNITED STATES PATENT OFFICE.

WALTER H. WOOD, OF SEATTLE, WASHINGTON.

CLOTHES-LIFTER.

1,253,450.

Specification of Letters Patent. Patented Jan. 15, 1918.

Application filed January 17, 1916. Serial No. 72,629.

To all whom it may concern:

Be it known that I, WALTER H. Wood, citizen of the United States, residing at Seattle, in the county of King and State of Washington, have invented a certain new and useful Improvement in Clothes-Lifters, of which the following is a specification.

My invention relates to improvements in clothes lifters such as are used for lifting and removing clothes from the wash-boiler in which they have been boiled, and the object of my invention is to provide a handy clothes lifter of reticular form which may be disposed within a wash-boiler adjacent to the bottom thereof to support clothes during the operation of boiling them, and which may be operated to lift all of such clothes out of said wash-boiler by a single movement, or to lift them out all together step by step to rest them at one stage after another, thus to permit the water in which they were boiled to drain from them.

I accomplish this object by devices illustrated in the accompanying drawings where- 25 in Figure 1 is a plan view of a clothes lifter embodying my invention as it appears unassociated with a wash-boiler and with all of its parts disposed in the same plane; Fig. 2 is an enlarged view of the 30 same in side elevation as it appears in one of its serviceable positions in association with a wash-boiler which is shown in vertical mid-section; and Fig. 3 is a plan view of a modified form of a detail of my in- 35 vention.

Referring to the drawings, throughout which like reference numerals indicate like parts, 4 designates a reticular rack, whose shape in outline corresponds to the contour 40 of the bottom 5 of a wash-boiler 6 of the most common form.

Articulated to the opposite ends 7 and 8 of said rack 4, by means of rings 9 and 10 respectively, are end links 11 and 12 of two 45 oppositely disposed suspension chains whose other end links 13 and 14, respectively, are formed to adapt them to serve as hand-holes by which the structure may be lifted.

Between the links 11 and 13 of one of said 50 chains are intervening links 15, 16 and 17, and between the links 12 and 14 of the other of said chains are intervening links 18, 19 and 20.

The several links of both of said suspen- 55 sion chains are each formed of a single piece of wire bent to form a link that is about

as broad as it is long, and on each side of each of the links 11, 15, 16 and 17 and of each of the links 12, 18, 19 and 20, on that end more distant from the rack 4, is formed 60 a hook, as hooks 21, 22, 23 and 24, so that when the rack 4 is disposed within the wash-boiler 6 the required opposite pairs of said hooks may be disposed to hook on to the top edges of the respective opposite end 65 walls of said wash-boiler 6 to suspend the rack 4 at a desired one of different distances from the bottom 5 of said wash-boiler 6, as shown in Fig. 2 where the hooks 24 of the links 17 and 20 are disposed in the manner described to suspend the rack 4 in a plane not far distant from the bottom 5 of the wash-boiler 6.

To utilize my clothes lifter, it is disposed within a wash-boiler 6 as shown in Fig. 2 75 and thereupon a suitable quantity of water is poured into said wash-boiler 6, then the clothes to be boiled are deposited on the rack 4 whereupon the links 13 and 14 are grasped by one's hand and the suspension 80 chains are raised to disengage the hooks 24, then the links 13 and 14 are moved toward each other and the rack 4 is lowered to rest on the bottom 5, the top ends of the sus- 85 pension chains being then thrown inwardly to rest on the top of the pile of clothes, and thereupon a cover, not shown, may be dis- 90 posed in its place to cover said wash-boiler during the operation of boiling said clothes.

After the operation of boiling said clothes 90 then the wash-boiler is uncovered and the links 13 and 14 are again grasped to raise the rack 4, with its load of clothes, wholly out of the wash-boiler by a single movement 95 and then carry them to a desired point for further treatment, or, the suspension chains may be raised by successive movements suc- 100 cessively to engage the opposite ones of the different pairs of hooks 21, 22, 23 and 24 with the top edges of the opposite end walls of the wash-boiler 6 thus, in an obvious manner, to suspend said rack 4 in successively higher planes for such suitable length of time as may be required to drain the water from said clothes.

In order to prevent clothes from being caught by the different hooks, as hooks 21, 22, 23 and 24, each or any number of the several links of the suspension chains, like the links 11 and 15 and the links 12 and 18, 110 may be provided with shields of wires dis- 115 posed criss-cross between the cross-bars of

adjacent links, like the wires 25 on said links 11, 15, 12 and 18 as shown more clearly in Fig. 1, or said links may each be provided with a shield of thin sheet metal extending 5 between the opposite bars thereof, like the shields 26 shown in Fig. 3.

When a clothes lifter, embodying my invention as hereinbefore described, is made of such small size as will adapt it for use 10 in connection with the smaller sizes of wash-boilers, it may be lifted from the wash-boiler when loaded with clothes, with ease by a laundress, but since the employment of a larger size of such clothes lifter in connection with a larger wash-boiler might involve the expenditure of much greater energy, I have provided a looped cord, as looped cord 27, attached to the rings 9 and 10 respectively, as more clearly shown in Fig. 2, which may be disposed to extend upwardly each between the mass of clothes and the adjacent respective one of the suspension chains so that when it is desired to raise the rack 4 with the clothes thereon, then a clothes stick 28 of common form, as indicated by dotted lines in Fig. 2, may be inserted in the looped cord 27 and the top edge of the wash-boiler may be used as a fulcrum, whereby the clothes stick 28 may 25 be manipulated as a lever to raise the suspension chain one link at a time first on one end of the wash-boiler 6 and then on the other end thereof alternately and successively to engage the hooks 23, 22 and 21 with the top edge of the wash-boiler 6 in an obvious manner to drain the water from the clothes and after the rack 4 is suspended 30

ed by the hooks 21 for a sufficient length of time to complete the draining of the water from the clothes, then two persons may lift 40 and carry the clothes to a desired point by grasping the links 13 and 14.

The rack 4, instead of being made of woven wire stretched on a frame in a manner shown, may consist of a plate of sheet 45 metal perforated with numerous holes through which water may drain from the clothes disposed thereon.

Obviously, changes may be made in the forms, dimensions and arrangement of parts 50 of my invention without departing from the spirit thereof.

What I claim is:

A clothes lifter for wash boilers including a reticulated rack, and means attached 55 to opposite edge portions of said rack for adjustably supporting the same at different distances above the bottom of a wash boiler, each of said means including a plurality of U-shaped links each having its ends loosely 60 coiled about the adjacent link between the leg portions thereof to hingedly connect the same, said ends of all the links being extended to provide a series of spaced integral pairs of hooks adapted to engage over the 65 top edge of a wash boiler.

In witness whereof, I, hereunto subscribe my name this 3rd day of January A. D., 1916.

WALTER H. WOOD.
